ATTORNEY.

UNITED STATES PATENT OFFICE.

OWEN P. WOLCOTT, OF PORTLAND, OREGON.

DISPLAY HOLDER.

Application filed February 21, 1925. Serial No. 10,749.

My invention relates to display holder where articles of merchandise may be fastened and displayed.

The objects of my invention are to construct a holder that may be fastened to a wire, cord, cloth or the wall by suspension hooks having attached thereto a spring clip to fasten and hold the articles of merchandise. I obtained these objects by the mechanism illustrated in the accompanying drawings of which:

Figure 1 is a side elevation of the device.

Figure 2 is a bottom plan view of device as shown in Figure 1.

Figure 3 is a side elevation of the device as connected in multiples for suspension for display of merchandise.

Similar numbers refer to similar parts throughout the several views: Number 1 is the body of the device; number 2 is the ears supporting clips; number 2^a is the pin extending through the ear supporting clips; number 3 is the spring clips; number 4 is the coil spring; number 5 is the suspension hook; number 6 is the suspension holes at the end of the body; number 7 is the suspension holes in the middle of the body.

It will be observed that at each end of the body 1 is the two hooks 5 near the end of the body 1, there is provided the ears for the supporting clips 2, the ear is attached to the body 1 so that there is an ear on each side of the body 1 opposite each other and extending from one ear to the other and through the spring clip 3 and coil spring 4 is pin 2^a. At each end of the body 1 there is provided two holes 6 and in the middle of the body is provided four holes 7.

It will also be observed that these holders may be joined together and used in multiples and that the holder may be used by hooking

the same upon any convenient article and that the articles of merchandise may be fastened upon the same by means of spring clips. 45

I am aware that the ears and supporting clips and spring clips have been long in use but the combination of the same with the body, the hooks, and the holes in the body is a new and useful combination. 50

Having fully described my invention I claim and desire to protect by Letters Patent:

1. In a display holder comprising a body member, said body member having attached at each end thereof ears to which are attached clips suspending hooks attached to each end of said body member, a series of holes arranged in said body member so as to admit the joining together by a means of 55 said suspending hooks the holders to be used in multiples substantially as described.

2. A display holder, comprising a combination, a body member having attached near to each end thereof ears to which are 60 attached clips, suspending hooks at each end of said body member arranged so as to fit in a series of holes in like constructed display holders contained in the body member so as to join two or more holders by means 65 thereof together substantially as described.

3. In a display holder comprising a body member, ears attached to each end of said body member supporting clips attached thereto, suspending hooks at each end of said 70 body member, a plurality of holes arranged in said body member so that by means of said hooks display holders may be joined together substantially as described.

In witness whereof I have hereunto set my 80 hand.

OWEN P. WOLCOTT.
